(57)

CLAIM

The ornamental design for a wireless communication tag, as shown and described.

DESCRIPTION

FIG. 1 is a front elevational view of a wireless communication tag, showing the new design;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.

1 Claim, 6 Drawing Sheets
